United States Patent [19]

Kelly

[11] Des. 274,320

[45]  Jun. 19, 1984

[54] CABLE SUPPORTED PERSONNEL CARRIER

[75] Inventor: Terence Kelly, Birmingham, England

[73] Assignee: TI Reynolds Limited, Birmingham, England

[] Term: 14 Years

[21] Appl. No.: 374,484

[22] Filed: May 3, 1982

[30] Foreign Application Priority Data

Nov. 5, 1981 [GB] United Kingdom 81-1003436

[52] U.S. Cl. D12/37

[58] Field of Search D34/28, 33, 37; D12/1, D12/37; 105/148, 154, 155; 182/14, 37, 36, 144, 112, 150, 193

[56]

References Cited

U.S. PATENT DOCUMENTS

3,702,124 11/1972 Highland 105/154
4,163,480 8/1979 Highland 105/148

Primary Examiner—James M. Gandy

Attorney, Agent, or Firm—Kemon & Estabrook

[57]

CLAIM

The ornamental design for a cable supported personnel carrier, as shown and described,

DESCRIPTION

The FIGURE is a perspective view of a cable supported personnel carrier showing my new design, it being understood that the bottom of the carrier is substantially flat and unornamented.

U.S. Patent

Jun. 19, 1984

Des. 274,320